COMBINED HAMMER AND TACK LIFTER

Maurice E. Seaman, Wolverine, Mich.

Application October 7, 1954, Serial No. 32,576

Term of patent 7 years

(Cl. D54—13)

Figure 1 is a side elevational view of a combined hammer and tack lifter, showing my new design.

Figure 2 is a top end elevational view, the hammer portion being omitted for convenience of illustration.

Figure 3 is a fragmentary edge elevational view.

The dominant features of my design are shown in solid lines.

I claim:

The ornamental design for a combined hammer and tack lifter, substantially as shown and described.
